(57) **CLAIM**

The ornamental design for an opening in a brake caliper, substantially as shown and described.

DESCRIPTION

FIG. 1 is a perspective view of an opening of a brake caliper in accordance with the present invention.

FIG. 2 is a front elevational view of FIG. 1.

FIG. 3 is a side elevational view of FIG. 1; and,

FIG. 4 is a top plan view of FIG. 1.

The broken lines are for illustrative purposes only and form no part of the claimed design.
